UNITED STATES PATENT OFFICE.

HARRY LANDSIEDEL, OF POPLAR BLUFF, MISSOURI, ASSIGNOR TO DALTON ADDING MACHINE COMPANY, OF ST. LOUIS, MISSOURI, A CORPORATION OF MISSOURI.

ADDING-MACHINE.

1,078,358.

Specification of Letters Patent. Patented Nov. 11, 1913.

Application filed March 6, 1911. Serial No. 612,723.

To all whom it may concern:

Be it known that I, HARRY LANDSIEDEL, a citizen of the United States, residing at Poplar Bluff, Missouri, have invented a new and useful Adding-Machine, of which the following is a specification.

This invention relates to adding machines of that type which embody a movable carriage containing series of pins and keys operable to set the pins to represent numbers and to cause said carriage to move to operative position so that the numbers set up or represented by the pins in the carriage may be added or recorded.

15 A machine of that type is now in commercial use and is known as the "Dalton." The "Dalton" adding machine is constructed in substantial accordance with the adding mechanism of the adding and writing machine illustrated in Hopkins Patent, Number 1,039,130, dated September 24, 1912, whose British counterpart is found in British Patent Number 854 of 1904.

25 For convenience of illustration and description I have shown my present invention embodied in an adding machine of the "Dalton" type, but it will be apparent that the invention is adaptable to any machine containing a movable carriage, and that 30 many of the principles of the invention are adaptable to other machines, and I do not restrict myself to the use of the invention in any specific adding machine.

The adding mechanism of the machine described in the Hopkins patent above mentioned contains a movable carriage having series of pins arranged therein, an escapement and motor device for moving the carriage step by step laterally, and a series of 40 keys which are operable to set the pins in the carriage to represent numbers to be added or recorded and to cause the escapement and motor device to operate effectively to move the carriage to any desired position relative 45 to the adding and recording mechanisms, so that the numbers represented by the pins in the carriage may be added or recorded. This also is the arrangement of the department of the machine shown in the Hopkins 50 Patent Number 1,039,130 and a similar arrangement is employed in the "Dalton" adding machine as it is now on the market and known commercially. In all of said machines the pin carriage is moved step by step 55 as each digit key is operated and there is

no mechanism for indicating to the operator the numbers or digits represented in the carriage prior to the operation of the recording mechanism. Therefore, should the operator operate a wrong key, and fail to detect the error before operating the recording and adding mechanism, the incorrect number so set up or represented in the pin carriage would also be recorded and added; whereas, should the operator be enabled to 60 detect the error before operating the adding and recording mechanism, such error could be eliminated or corrected.

65 My present invention comprises mechanism operable to indicate the items or numbers as they are set up or represented in the pin carriage by operation of the keys, so that the operator will be informed at all times what number is represented in the pin carriage, such mechanism comprising a 70 novel registering device operated and controlled by the keys and the pin carriage effectively to indicate the digit of each key as it is operated, and is located in plain sight. The register is returned to idle or "clear" 75 position at the same time that the carriage returns to idle position and moves in unison and harmony with the pin carriage.

80 The machine includes a key device having connections for restoring the pin carriage 85 to idle position from any position in which it may be located. It also includes a back space key whereby the pin carriage may be moved step by step toward idle position effectively to remove from registering position 90 any one or more of the digits represented in the carriage. This last named key enables the operator to correct one or more digits of a number, without throwing out the entire number. The two keys mentioned are 95 also arranged to move the registering device (which I hereafter refer to as a register carriage) to the same extent as they move the pin carriage. The entire number can be 100 thrown out by use of the correction key, or one or more of the digits can be removed by use of the back space key. The operation of the pin carriage and the register carriage is uniform in whatever direction they may 105 move, whether in the setting up and registering of numbers, or in the correction and elimination of numbers or the digits thereof, or in their return to idle position after the adding and recording of numbers.

110 In the accompanying drawings, wherein

I have illustrated one embodiment of my invention:—Figure 1 is a view showing some of the working parts of a “Dalton” adding machine, and my invention embodied therein. Fig. 2 is a sectional view just below the key-board plate of the machine illustrating the item register carriage, and the connection which extends to the pin carriage to effect uniform movement of the pin carriage and the item register carriage. Fig. 3 is a plan view of the “Dalton” key board, and the item register mounted therein. Fig. 4 is an enlarged sectional view just below the key board plate. Fig. 5 is an enlarged sectional view of the key board, showing the item register, also in section. Fig. 6 is a sectional view on the line A—A of Fig. 7. Figs. 7 and 8 are detail views of the release device whereby the item register disks are released when the carriage in which they are mounted is returned to idle position. Fig. 9 is a view in front of the key-levers, showing the parts actuated thereby for setting the item register. Fig. 10 is a view showing the connections actuated by the key-levers for operating the register disks. Fig. 11 is a view of one of the connections in operation by a key, the pivotally supported racks being operated by a key and being engaged with an arcuate rack on an indicating disk. Fig. 12 is a view showing the correction key (the upper one) and the back space key (the lower one) and connections leading toward the pin carriage escapement device. Fig. 13 is a view corresponding to, and extended from, Fig. 12, showing the escapement for the pin carriage, and the connections from the correction key and the back space key for operating the escapement and the pin carriage, toward idle position. Fig. 14 is a plan view showing the pin carriage escapement device, and the connections which extend to the correction key and the back space key.

The adding mechanism of the machine of said Patent No. 1,039,130, and of said British Patent Number 854 of 1904, and the “Dalton” adding machine manufactured in substantial accordance therewith, includes a series of ten figures or digit keys 1, arranged in convenient relation in the key-board and having levers 2 extending rearwardly in the machine and pivotally supported at 2^a. The rear ends of said levers terminate in a longitudinal row and are provided with extensions 3 constituting hammers or drivers for setting the pins in the pin carriage.

The pin carriage 4 is movably supported on rails 5, extending transversely above the key levers. Series of pins 6 are mounted in the carriage and are movable by the hammers or drivers 3 so as to represent the numbers to be added or recorded when the keys 1 are operated. An escapement shaft 7 has an arm or lever 8 attached thereto,

and a link 9 connects said arm or lever with the carriage 4, so that when the said shaft 7 is operated it will control and move the pin carriage. (See Fig. 2.) The series of pins 6 are thus brought into operative position with respect to the hammers 3, each step of the carriage transporting another row or series of pins over said hammers. An escapement bar 10 extends across the key levers 2 and controls the operation of the shaft 7 and the other parts connected therewith through an escapement segment 11 on said shaft and a pawl 12 on said escapement bar. A spring 13 may be employed in connection with the carriage escapement shaft to actuate said carriage in one direction when said carriage is permitted to move by operation of the keys. The numbers thus set up or represented in the pin carriage may be recorded on paper supported on a platen or paper carriage 14, by operation of suitable recording mechanism comprising type carriers 15 and racks 16. Said racks also operate the adding and accumulating mechanism 17 effectively to cause said mechanism to add the numbers recorded. Record of the various items is made by use of type 18 on the type carriers 15 driven by hammers 19. The mechanism thus described is the same as that described in the aforesaid British patent, and in the Patent Number 1,039,130, and contained in the “Dalton” adding machine. It will be noted that the mechanism so far described does not include any device whereby the operator will be informed as to the value of any number represented in the carriage, or whether any number at all is represented therein.

The main shaft A controls the operation of the adding and recording mechanism. After the number has been set up in the pin carriage the shaft A is rocked, and the rod B is swung forwardly so as to permit the type-carriers 15 and the racks 16 to move until the depending heels 16^a on the racks engage with the pins set to represent the number. The hammers 19 then strike the type 18 and print the number. The shaft A is then rocked to its initial position and the rod B returns the type-carriers and racks to their idle position. The shaft A has an arm 20 carrying a pawl 21. When said shaft is rocked forwardly the pawl 21 becomes engaged with a pin 22 on a link 23 whose upper end is rigid on a rock shaft 24. Return movement of the pawl 21 draws back the link 23 until said pawl is disengaged from the pin 22 near the stopping point of said pawl. A link 25 connects the lower end of the link 23 with an arm 26 loose on the shaft 7, and having a lug 27 on its under side. An arm 28 which is rigid on the shaft 7 has a lug 29 on its upper side. When the link 25 is forced rearwardly the lug 27 engages the lug 28 and thereby rocks the shaft 130

7 effectively to return the carriage 4 to its idle position under the plate 30 (Figs. 2, 13 and 14) by which the set-up pins will be pressed down to their initial or idle adjustment ready for another operation. A spring 31 connecting the arm 26 with a stationary part restores said arm, the link 25, the link 23, and other connected parts to idle position after the pawl 21 releases said link 23. This operation is performed at each recording or adding operation, except in instances where a number is "repeated."

Key mechanism, commonly known as "error key mechanism," or "correction key mechanism," by which the pin carriage may be returned to idle position without operation of the adding or recording mechanisms, is also contained in these machines. Said mechanism comprises a stem and key 32 pivoted to one arm of a bell-crank lever 33 supported at 34, and a link 35 connecting the other arm of the lever 33 with an arm 36 attached to the rock shaft 24 (see Fig. 12).

From the foregoing it is obvious that depression of the key 32 will operate the link 25 effectively to restore the pin carriage to its initial or starting position and "clear" or dissipate any number set up in said carriage. A spring-actuated latch 37 is held out of engagement with the key 32 when the shaft A is idle, by a link 38 leading to a cam on said shaft. When the shaft is rocked the latch engages with the key 32 and prevents operation of said key while said shaft, and the adding and recording mechanism, or either of them, are operating. The above described error key or correction key mechanism is substantially the same as that contained in the said British patent, said application Serial Number 140,390, and the said "Dalton" machine. This mechanism, it will be noted, is operable to move the carriage to idle position, at a single operation, from whatever position said carriage may occupy. Frequently it is desirable to move the carriage only one or more steps toward idle position, to dissipate or eliminate a like number of digits from the

number set up or represented in the carriage. For this purpose I have equipped the machine with a back space key mechanism to move the carriage step by step toward idle position to remove or eliminate one or more figures from the number in said carriage, as desired. Said mechanism comprises a key, 39 pivoted to a bell-crank lever 40, from which a link 41 leads to a lever 42 near the rear of the machine (Figs. 12, 13 and 14). The lever 42 has pin-and-slot pivot connection with an arm 43 attached to a vertical rock shaft 44 on the upper end of which is an arm 45 carrying a pawl or dog 46 adapted to engage with the escapement segment 11 when the key 39 is de-

pressed and move the escapement and thereby the pin carriage one step toward idle position. An abutment 47 prevents turning of the pawl or dog, and a spring 48 holds said pawl or dog in proper adjustment. The latch 37 is also operative to engage with projections 49 on the key 39 and lock said key against operation when the adding and recording mechanism are in operation.

The present invention, comprising a visible item register, is embodied in and combined with the mechanism above described.

In the key-board plate above the series of keys an elongated opening 50 is formed. Two rails 51 are supported below the key-board plate and the item register or indicator carriage on said rails. Said carriage comprises a plate 52 and two end pieces 53, and rollers 54 supporting the carriage on the rails. A shaft 55 is supported by the end plates 53, and the register or indicator devices are mounted on said shaft. Said register or indicator devices are arranged in pairs, each device being substantially in the form of the segment of a disk, having on its peripheral edge a flange 56. In each pair of segments the flange of one segment operates within the flange of the other, as shown in Figs. 2 and 4. One of said flanges in each pair of registering segments has engraved thereon the figures or digits from "1" to "5," inclusive, and the other flange of each pair has engraved thereon the remaining figures or digits "6" to "9," inclusive, and "0," so that the ten figures are represented in each pair of registering devices. In registering the digits "1" "2" "3" "4" "5" in any order, only that registering device carrying such figures or digits will be actuated, and, in registering the other digits in any order, only the registering device carrying such digits will be actuated.

The shaft 55 has a link 56^a pivoted to its inner end, and an arm 57, attached to a rock shaft 58, is connected to said link, so that when said rock shaft is operated, the item register carriage will be correspondingly moved. An arm 59 on the rock shaft 58 is connected to an arm 60 on the escapement shaft 7 by a link 61 (Figs. 1 and 2). Through these connections the escapement shaft 7 which controls step by step movement of the pin carriage 4, also actuates the item register carriage, step by step from right to left with respect to the operator facing the machine. In normal or idle position, the item register carriage is at the right, one space or step removed toward the right from the open or registering space as indicated in Fig. 3, so that the first movement of the said item register carriage will position one of the registering segments in view through the open space 50. Each successive movement of the item registering carriage positions another one of the regis-

tering segments in view, such movements of the item registering carriage being in conformity with the lateral step by step movement of the pin carriage 4 in which the numbers that are to be added and recorded are set up or represented by operation of the keys 1. In normal or idle position the registering segments are held in a forward adjustment so that all of the figures or digits thereon, except the "0," are below and concealed by the plate 52. When any numeral or digit key is operated, the corresponding registering segments will likewise be operated to present the proper figure or digit in view through the open space 50. This movement is effected by suitable connections whereby each key will operate the corresponding registering devices in proportion to the value of the key.

Two alined shafts 62 and 63 are supported in bearings under the keys. The shaft 62 has forwardly extending arms 64 which support a rod 65 and the shaft 63 has forwardly extending arms 66 which support a rod 67. Springs 68 (Fig. 5) connect depending arms 69 on the shafts 62 and 63 with the stationary part of the machine and are effective to uphold the rods 65 and 67 close to the lower edge of the key levers. The levers for the "1" "2" "3" "4" "5" extend over the rod 65 and are different distances from said rod in proportion to the value of the keys—that is to say, the "1" key lever is nearest the rod 65, the "2" key lever is a slight distance removed therefrom and the key levers for the figures "3" "4" and "5" are at increasingly greater distances from the rod 65. When the "1" key is depressed the rod 65 will be pressed downwardly an equal distance and the shaft 62 will be correspondingly rocked, while operation of the "2" key will rock the shaft 62 a distance less than does the "1" key corresponding to the difference in value between the two digits. This difference in the motion imparted to the shaft 62 by operation of the digits keys is maintained by all of the digits keys which affect said shaft so that the "5" key will rock said shaft only a very slight distance, much less than does the "1" key, for instance. The levers for the "6", "7", "8", and "9" keys are similarly arranged with respect to the rod 67, and rock the shaft 63 different distances conforming to the value of the keys depressed. The shafts 62 and 63 transmit this motion to the registering segments in the item register carriage, and since no motion is required to register the "0" in sight through the open space 50, the "0" key causes no motion of the item register device except lateral movement to the item register carriage which is transmitted thereto from the lateral movement of the pin carriage 4.

The shaft 62 has an upwardly extending

arm 70 to which is pivoted a bar or link 71, the rear end of which has an elongated slot 72 through which projects a square supporting rod 73. The shaft 63 has an arm 74 similar to the arm 70 and a link or bar 75 similar to the link or bar 71, and likewise supported on the square supporting rod 73 (Figs. 2 and 6). Each of the bars or links 71 has pivoted thereto a number of links 76 which support a rack 77 and a pawl 78 is pivoted to each rack 77 and is permitted a slight vertical movement by a pin 78 on the rack extending into a slot 80 in the pawl. In idle position the front ends of the pawls abut against the supporting rod 73 permitting the racks 77 to rest in their lower adjustment as shown in Fig. 5.

Each registering segment has an arcuate rack 81 on its lower edge, said racks being in a plane just above the racks 77. The arrangement is such that the racks 81 on these registering devices containing the digits "1" to "5" inclusive are moved successively and positioned immediately over that rack 77 which is on the bar or link 71 which, as previously described, is actuated by the keys "1" to "5" inclusive. Similarly, the racks 81 on the registering devices containing the digits "6" to "9" inclusive (and the "0" character) are moved and positioned successively over rack 77 which is carried by the bar or link 75 which, as previously described, is operated by the keys "6" to "9" inclusive. When any digit key is depressed and its bar or link 71 or 75 is moved forwardly the pawl 78 by engagement with the supporting rod 73 raises the rack 77 until it meshes with the rack 71 immediately thereover. An abutment 82 is on each link or bar 71 and 75 (Figs. 5 and 10) and is brought against the rear end of the rack 77 by the forward movement of the link or bar 71 and 75 when said links or bars are so operated. At the time of said engagement of the abutment 82 with the rack 77 the pawl 78 is above the supporting rod 73 so that the rack 77 now in mesh with its proper rack 81 will be moved forwardly a distance corresponding to the value of the key depressed and will transmit proper motion to the registering segment in the item register carriage. This motion is sufficient to position the digit on the registering device so operated in view through the open space 50. When the keys are released the shafts 72 and 73 are returned to idle position by their springs 78 which also return the links or bars 71 and 75 to the racks 77 carried thereby. It will be observed that the racks 77 during their backward movement do not operate the registering devices, but are lowered by gravity to their idle positions disengaged from such registering devices.

The registering segments have arcuate slots 83 and the side plates 53 of the item

- register carriage support a rod 84 extending through said slots. On said rod 84, and close to each registering segment, a latch pawl 85 is pivoted. In idle position of the 5 item register carriage the rear ends of said pawls (except that one at the left relative to the operator) are under a bar 86 supported behind the item register carriage, and are held out of engagement with the teeth 87 on 10 the registering segments, said pawls being provided with hooks 88 which engage with said teeth to latch said segments in registering position at the proper time. The first 15 operation of a key causes the pawl 85 at the left to engage with and lock the proper registering segments, and releases the next one of the pawls 85 by moving it past an oblique shoulder 89 on the plate or bar 86. Since one of the registering segments is positioned 20 by the key at the same time the pawl at the left will engage with the teeth 87 on the registering segment so positioned and hold it in such position so that the figure or digit thereon corresponding to the key operated 25 will be presented to view through the open space 50. The hook 88 on each pawl 85 is long enough to engage with the teeth 87 of both members of that pair of registering segments with which said pawl co-operates 30 and a spring 90 is provided to actuate each registering segment to its idle position when released from the pawl. A spring 91 actuates the pawls 85 so as to engage them with the teeth of the registering segments when 35 said pawls are released from the bar 86 by movement of the item register carriage, as above described. Each registering segment operated will thus be latched and retained in registering position when operated. After 40 each number set up or represented in the pin carriage 4 is added or recorded said carriage is automatically returned to idle position, as hereinbefore described, which movement rocks the escapement shaft 7 and operates 45 the arm 60 attached to said shaft. The connection from the arm 60 to the item register carriage also moves said carriage to its idle position at the right of the machine with respect to the operator, and this movement 50 of the item register carriage releases the registering segments in said carriage and permits them to return to idle or "clear" adjustment in the carriage. While the item register carriage is moving toward its idle 55 position the rear ends of the pawls 85 move along under the bar 86 toward the oblique shoulder 89 on said bar and just prior to rubbing against said shoulder each pawl engages a shoulder 92^a on a trip plate 92 which 60 is yieldingly supported by the bar 86. Said plate has oblique slots 93 through which extend pins or studs 94 supporting said plate on said bar 86. A spring 95 connecting said plate 92 with the bar 86 holds said plate 92 65 in its highest position until engaged by the end of a pawl 85 moving toward idle position. When any one of the pawls 85 engages the shoulder 92^a on the plate 92 during the movement of said pawl toward idle position it has the effect of moving said plate 92 obliquely downward which also presses downwardly the rear ends of the two pawls engaged therewith. This movement is continued until the end of the pawl nearest the oblique shoulder 89 passes under the wider 70 portion of the bar 86, at which time the plate 92 is released and restored to idle position by its spring 95 ready to be engaged by the next adjacent pawl. 75 It will be noted that the last or left hand pawl 85 does not pass under the plate or bar 86, but remains in the position shown in Fig. 6, said pawl having been released from its registering segment by the movement of the plate 92 caused by the previously returned 80 pawl. 85 A series of arms 97 are attached to the shafts 62 and 63 and extend alongside of the levers 2. Abutments 98 are on the levers 2 and receive the impact of the arms 97, and thereby prevent excess movement or rotation of the said shafts 62 and 63 so as to assure correct operation of the registering segments. 90 Whenever the pin carriage 4 is returned to 95 its idle position without adding or recording any number that may have been set up or represented therein by operation of the correction mechanism or the back space mechanism, it is plain that the item register carriage will also be moved toward idle position to "clear" therefrom one or more of the digits, or the entire number, as desired, depending on whether the correction key or the back space key be operated. This item 100 register mechanism and the pin carriage 4 in which the numbers are set up or represented preliminarily to adding or recording them, are connected so that their operation is uniform throughout. The top plate 52 is preferably provided with a series of openings or 105 holes 96 through which the registering segments and the numeral or digits thereon will be visible as shown in Figs. 3 and 5. 110 I have shown the item registering mechanism actuated directly from the keys and located just above the key-board in convenient position so that the operator may readily observe both the keys and the registering mechanism while operating the machine. I 115 do not restrict myself to this arrangement, since the registering mechanism is readily adaptable to other embodiments, and may be located in any preferred position. I am aware that there may be various modifications in the construction, arrangement and 120 operation of the various parts without the least departure from the nature and principle of my invention, and I do not restrict myself to specific devices, but 125 130

What I claim and desire to secure by Letters Patent of the United States is—

- 5 1. In an adding machine, the combination with a movable carriage, and means for setting up or representing numbers in said carriage, of an item register movable in unison with said carriage, and registering devices in said item register effecting a visible registration of the numbers set up or represented in said carriage, substantially as specified.
- 10 2. In an adding machine, a carriage, escapement mechanism for moving said carriage, and keys operable to set up or represent numbers in said carriage and to cause said escapement to operate, in combination with an item registering carriage controlled by said escapement mechanism, and a registering device in said last-named carriage indicating the numbers as they are set up or represented in said first-named carriage substantially as described.
- 15 3. In an adding machine, a series of keys, a carriage, and registering devices in said carriage effecting a visual registration of the numbers represented by the keys operated, in combination with another carriage controlling said first-named carriage and a platen for holding paper to receive records of said numbers, substantially as specified.
- 20 4. In an adding machine, a series of numeral keys, a carriage, a second carriage controlling said first-named carriage, mechanism for moving said carriages when said numeral keys are operated, mechanism in said first-named carriage indicating visually the numbers represented by the keys operated, mechanism for recording said numbers after said carriages have been moved, and mechanism for restoring said carriage and the registering devices to idle position after operation, substantially as described.
- 25 5. In an adding machine, a carriage, a second carriage controlling said first-named carriage, keys, registering devices in one of said carriages, and connections whereby said keys will operate said registering devices effectively to produce a visible registration of numbers represented by the keys operated, in combination with mechanism for recording said numbers respectively, after said numbers have been registered, substantially as specified.
- 30 6. In an adding machine, a carriage, a second carriage controlled by said first-named carriage, keys, registering devices in said second carriage, connections whereby said keys will operate said registering devices effectively to produce a visible registration of the numbers represented by the keys operated, and mechanism controlled by said keys for moving said carriages laterally and mechanism for adding said numbers after said carriages have been moved, substantially as described.
- 35 7. In an adding machine, a carriage, a second carriage controlled by said first-named carriage, registering devices in said second carriage, keys, and connections whereby said keys may be caused to operate said registering devices and move said carriages effectively to produce visible registration of the numbers represented by the keys operated, in combination with adding mechanism operable to add the numbers registered in said carriage, substantially as specified.
- 40 8. In an adding machine, a carriage, a second carriage controlled by said first-named carriage, registering devices in said second carriage, keys and connection whereby said keys may be caused to operate said registering devices and move said carriages effectively to produce visible registration of the numbers represented by the keys operated, in combination with mechanism operable to add said numbers, and mechanism operable to record said numbers, substantially as specified.
- 45 9. In an adding machine, a carriage, a second carriage controlled by said first-named carriage, registering devices in said second carriage, numeral keys operable to set up numbers in said first-named carriage, and devices under control of a plurality of said keys whereby one key may be caused to operate any desired number of said registering devices effectively to produce a visible registration of the number represented by the keys operated, and means for restoring said registering devices to idle position, substantially as described.
- 50 10. In an adding machine, a carriage, a second carriage controlled by said first-named carriage, registering devices in said second carriage, keys, connections whereby said keys may be caused to operate said registering devices effectively to produce a visible registration of the numbers represented by the keys operated, and mechanism controlled by said keys for moving said carriages laterally and mechanism for adding said numbers after said carriages have been moved, substantially as described.
- 55 11. In an adding machine, a movable carriage, means for setting up numbers in said carriage, mechanism for moving said carriage laterally, a second carriage movable in unison with said first-named carriage, registering devices in said second-named carriage, and devices for adjusting said registering devices effectively to indicate visually the numbers set up in said first-named carriage, substantially as specified.
- 60 12. In an adding machine, the combination with a movable carriage, series of pins in said carriage, keys operable to set said pins to represent numbers, and means for recording numbers registered in said carriage

after said carriages have been moved, substantially as specified.

7. In an adding machine, a carriage, a second carriage controlled by said first-named carriage, registering devices in said second carriage, keys, and connections whereby said keys may be caused to operate said registering devices and move said carriages effectively to produce visible registration of the numbers represented by the keys operated, in combination with adding mechanism operable to add the numbers registered in said carriage, substantially as specified.

8. In an adding machine, a carriage, a second carriage controlled by said first-named carriage, registering devices in said second carriage, keys and connection whereby said keys may be caused to operate said registering devices and move said carriages effectively to produce visible registration of the numbers represented by the keys operated, in combination with mechanism operable to add said numbers, and mechanism operable to record said numbers, substantially as specified.

9. In an adding machine, a carriage, a second carriage controlled by said first-named carriage, registering devices in said second carriage, numeral keys operable to set up numbers in said first-named carriage, and devices under control of a plurality of said keys whereby one key may be caused to operate any desired number of said registering devices effectively to produce a visible registration of the number represented by the keys operated, and means for restoring said registering devices to idle position, substantially as described.

10. In an adding machine, a carriage, a second carriage controlled by said first-named carriage, registering devices in said second carriage, keys, connections whereby said keys may be caused to operate said registering devices effectively to produce a visible registration of the numbers represented by the keys operated, and mechanism controlled by said keys for moving said carriages laterally and mechanism for adding said numbers after said carriages have been moved, substantially as described.

11. In an adding machine, a movable carriage, means for setting up numbers in said carriage, mechanism for moving said carriage laterally, a second carriage movable in unison with said first-named carriage, registering devices in said second-named carriage, and devices for adjusting said registering devices effectively to indicate visually the numbers set up in said first-named carriage, substantially as specified.

12. In an adding machine, the combination with a movable carriage, series of pins in said carriage, keys operable to set said pins to represent numbers, and means for recording numbers registered in said carriage

moving said carriage when said keys are operated, of a registering mechanism operated directly by said keys effectively to produce visible registration of the numbers represented in said carriage, substantially as described.

13. In an adding machine, a movable carriage, pins in said carriage, keys for adjusting said pins to represent numbers, means for moving said carriage, an escapement mechanism controlling the movement of said carriage, a registering carriage separate from said first-named carriage, mechanism in said registering carriage indicating numbers represented in said first-named carriage, and connections whereby said escapement mechanism will control said registering carriage, substantially as described.

14. In an adding machine, a movable carriage, mechanism for setting up numbers in said carriage, and mechanism for recording said numbers, in combination with a registering carriage operable to indicate the numbers set up in said first-named carriage, and means for moving said registering carriage in unison with said first-named carriage, substantially as described.

15. In an adding machine, a carriage, mechanism for setting up numbers in said carriage, means for moving said carriage, a registering carriage, and means in said registering carriage indicating numbers set up in said first-named carriage, in combination with correction mechanism whereby said carriages and said registering mechanism may be caused to return to idle position.

16. In an adding machine, a carriage, a second carriage controlled by said first-named carriage, rails supporting said second carriage, registering devices in said second carriage, keys operable to adjust said registering devices and cause said second carriage to move effectively to produce visible registration of the numbers struck on said keys, and adding mechanism operable to add the numbers so registered, substantially as specified.

17. In an adding machine, a carriage, a second carriage controlled by said first-named carriage, rails supporting said second carriage, registering devices in said second carriage, keys operable to adjust said registering devices and cause said carriage to move effectively to produce visible registration of the numbers struck on said keys, and mechanism operable to record the numbers so registered, substantially as specified.

18. In an adding machine, a carriage, a second carriage controlled by said first-named carriage, rails supporting said second carriage, registering devices in said second carriage, keys operable to adjust said registering devices and cause said carriage to move effectively to produce visible regis-

tration of the numbers struck on said keys, adding mechanism operable to add the numbers so registered, and mechanism operable to record the numbers so registered, substantially as specified.

19. In an adding machine, a carriage, a second carriage controlled by said first-named carriage, rails supporting said second carriage, escapement mechanism for moving said second carriage on said rails, adding mechanism, mechanism for effecting visible registration of numbers in said second carriage preliminary to operation of said adding mechanism, and means for dissipating any numbers registered in said second carriage.

20. In an adding machine, a carriage, mechanism for setting up numbers in said carriage, separate devices for producing a visible indication of the numbers set up in said carriage incidentally to the setting of said numbers, and mechanism operable to record the numbers set up in said carriage, substantially as specified.

21. In an adding machine, recording mechanism, a carriage whose operation is necessary before said recording mechanism may be operated, means for setting up numbers to be recorded, and means supported independently of said carriage for effecting a visible registration of the numbers set up, substantially as specified.

22. In an adding machine, a series of type-carriers, a carriage whose operation is necessary before said type-carriers may be operated, means for setting up numbers to be recorded by said type-carriers, and means supported independently of said carriage for effecting a visible indication of the numbers before operation of said type-carrier, substantially as specified.

23. In an adding machine, adding mechanism, a carriage whose operation is necessary before said adding mechanism may be operated, means for setting up numbers to be added, and means supported independently of said carriage for effecting a visible indication of the numbers to be added incidentally to the setting up of said numbers, substantially as specified.

24. In an adding machine, the combination with type-carriers, a platen arranged to feed paper to said type-carriers, means for visibly indicating or registering numbers to be recorded by said type-carriers, keys whose operation is necessary before said numbers may be indicated or registered, means for operating said type-carriers, stops for stopping and holding said type-carriers stationary adjacent to said platen in position to record the numbers indicated or registered, a carriage operable to set said stops, and means for recording the number indicated while said type-carriers are held stationary, substantially as specified.

25. In an adding machine, a series of stops, a carriage operable to set said stops to represent numbers, and a second carriage operating to effect visible indication of the 5 numbers represented by said stops incidentally to the setting up of said stops.

26. In an adding machine, a series of stops, a carriage operable to set said stops to represent numbers, and means for operating 10 said carriage, in combination with a second carriage and means in said second carriage operated incidentally to the operation of said first-named carriage to effect visible indication of the numbers represented 15 by said stops.

27. In an adding machine, a series of stops, a carriage operable to set said stops to represent numbers, means for operating 20 said carriage, a second carriage, means in said second carriage operable incidentally to the operation of said first-named carriage to effect a visible indication of the numbers represented by said stops, and means for recording said numbers, substantially as 25 specified.

28. In an adding machine, a series of stops, a carriage operable to set said stops to represent numbers, means for operating 30 said carriage, a second carriage, means in said second carriage operable incidentally to the operation of said first-named carriage to effect a visible indication of the numbers represented by said stops, and means for adding said numbers, substantially as 35 specified.

29. In an adding machine, a series of stops, a carriage operable to set said stops to represent numbers, means for operating 40 said carriage, a second carriage, means in said second carriage operable incidentally

to the operation of said first-named carriage to effect a visible indication of the numbers represented by said stops, and mechanisms for recording and adding said numbers, substantially as specified.

45

30. In an adding machine, the combination with type-carriers, a platen arranged to feed paper to said type-carriers, means for visibly indicating numbers to be recorded by said type-carriers, keys for operating 50 said indicating means, a carriage supported independently of said indicating means, and stops controlled by said carriage for limiting movement of said type-carriers, substantially as specified.

55

31. In an adding machine, the combination with type-carriers, stops for limiting movement of said type-carriers in their recording operations, a carriage for moving said stops to operative position, means for 60 visibly indicating numbers to be recorded by said type-carriers, and keys whose operation controls said carriage and said indicating means, substantially as specified.

32. In an adding machine, adding mechanism, indicators for said adding mechanism, a carriage whose operation is necessary before said actuators may be moved, means separate from said carriage for indicating visibly the numbers to be added prior to operation of said adding mechanism, and means for operating said actuators, substantially as specified.

65

In testimony whereof I have hereunto set my hand in the presence of two witnesses. 75

HARRY LANDSIEDEL.
